(57) **CLAIM**

The ornamental design for a beverage holder, as shown and described.

DESCRIPTION

FIG. 1 is an exploded front perspective view of the beverage holder showing my new design;

FIG. 2 is an exploded rear perspective view thereof;

FIG. 3 is an exploded right side view thereof;

FIG. 4 is an exploded left side view thereof;

FIG. 5 is an exploded top plan view thereof;

FIG. 6 is an exploded bottom plan view thereof;

FIG. 7 is a rear perspective view, showing the attachment straps;

FIG. 8 is a rear perspective view, showing two attachment straps; and,

FIG. 9 is a side view, showing the beverage holder in use.

The beverage holder is characterized by convex compartments with a decorative cover.
